HIGHWAY SIGNAL OR SIMILAR ARTICLE

Samuel J. Hatton, New Castle, Del., assignor, by mesne assignments, to Hi-Way Safety Equipment Company, Wilmington, Del., a corporation of Delaware

Filed June 7, 1961, Ser. No. 65,507

Term of patent 3½ years

(Cl. D72—1)

FIG. 1 is a top plan view of a highway signal or similar article showing my new design;

FIG. 2 is a front elevation thereof as shown in FIG. 1;

FIG. 3 is a rear elevation thereof as shown in FIG. 1;

FIG. 4 is a side elevation thereof as seen from the right of FIG. 2;

FIG. 5 is a side elevation thereof as seen from the left of FIG. 2;

FIG. 6 is a top plan view of a modified form of the highway signal or similar article shown in FIG. 1;

FIG. 7 is a front elevation thereof as shown in FIG. 6;

FIG. 8 is a rear elevation thereof as shown in FIG. 6;

FIG. 9 is a side elevation thereof as seen from the right of FIG. 7; and

FIG. 10 is a side elevation thereof as seen from the left of FIG. 7.

The essential features of my design reside in the portions shown in full lines.

I claim:

The ornamental design for a highway signal or similar article, as shown and described.
